TRANSVERSELY EXPANSIBLE UMBRELLA STICK

Jack J. Kesten, New York, N. Y.

Application January 17, 1951, Serial No. 206,397

3 Claims. (Cl. 135—20)

1

This invention relates to umbrella construction and, more particularly, to a transversely expandable stick or standard for an umbrella.

It is an object of the instant invention to provide an umbrella stick that will permit centering the protective covering over the body without substantially increasing the weight as compared with the common types of umbrellas.

A further object is to provide a stick of such design that the stick itself will yield before damage to other parts of the structure occurs.

Other objects of the instant invention will become apparent in the course of the following specification.

In the attainment of these objectives, the stick is constituted of an upper segment, an intermediate transversely expandable linkage system, and a lower segment slidable in a handle member. Both the segments and the links of the linkage system when collapsed are so designed that the collar will slide over all the members when the umbrella is being closed and opened. In the open position, the links of the linkage system expand to provide a frame through which the head of a person passes when the cover is centered over the body. Simple and effective means are provided for locking the members of the stick together either in the open or the closed position of the umbrella.

The invention will appear more clearly from the following detailed description when taken in conjunction with the accompanying drawings showing by way of illustration a preferred embodiment of the inventive concept.

In the drawings:

Figure 1 is a front view of the umbrella stick constructed in accordance with the principles of this invention with a portion of the umbrella covering broken away to more clearly show the construction;

Figure 2 is a sectional view taken along 2—2 of Figure 1;

Figure 3 is a fragmentary view of the stick taken in the direction of 3—3 of Figure 1, but on an enlarged scale;

Figure 4 is a fragmentary elevational view of the upper part of the stick shown in Figure 1, but in the partially lowered position of the umbrella and on an enlarged scale;

Figure 5 is a sectional view taken along 5—5 of Figure 4;

Figure 6 is a side view of the stick shown in Figure 4; and

Figure 7 is similar to Figure 4 but in the raised position of the umbrella and in the expanded position of some members of the linkage system.

2

Referring now in greater detail to the drawings where like reference numerals indicate like parts reference numeral 10 indicates the stick or standard, and 11 the known rib supporting collar 5 slidable on the stick.

The stick 10 is constituted of a top segment 12, an intermediate transversely expandable linkage system 13 (Fig. 1), and a bottom segment 14.

The top segment 12 is formed from any suitably 10 rigid material and is of circular cross section. Since the collar 11 is intended to slide along the segment, the latter has a diameter less than the inside diameter of the collar. One end of the segment supports the ribs and covering in a known manner while the opposite or free end is slotted to any desired depth and width. A tongue 15 is inserted in the slot and held in place by the rivets 16 and 17. The sides of the tongue are made flush with the rounded periphery of the segment and the free end of the tongue, not shown, is rounded.

Coacting with the top segment is the transversely expandable linkage system 13 of two members. Each member of the system is constituted 25 of the upper legs 18 and 19 (Fig. 1) and the lower legs 20 and 21. Both upper legs may be of equal length and both lower legs may be of equal length and greater than the length of the upper legs as illustrated. Each leg is of half-round or semi-

30 circular cross section having a flat base surface portion subtending a surface of semicircular cross section on a radius equal to that of the aforementioned top segment. In addition, the flat surface portion of each end of each leg is recessed as most clearly shown in Figures 3 and 6, the inner edge of the recess being perpendicular to the plane of the recess and at any desired angle to the center line of the leg as later shown. The depth of each recess is made substantially equal

35 to one-half the thickness of the previously mentioned tongue 15. However, it is not necessary that all of the recesses be of the same depth as long as the outer surfaces of the various components of the stick are maintained or can be 40 made flush to provide a continuous guideway over the segments and linkage system for the slidable passage of the collar.

At the top, the recesses of the upper legs are pivotally attached on opposite sides of the tongue 45 15 by the pivot pin 25, the outer end extremities of the recess being rounded to permit rotation around the rounded end of the tongue.

The opposite end of each upper leg 18 and 19 is pivotally attached to the end of the lower leg 50 20 and 21, respectively, by a plate 22 (Fig. 3), the plates having a height or thickness relatively

equal to the depth of the recesses. One end of each plate is fastened in one recess by the rivets 23 while the protruding end across the joint of the abutted ends of the legs is pivotally fastened in the recess of the opposite leg by the pivot pin 24. One side of at least one recessed end of one leg, where the legs are pivotally connected, as well as the end of the plate adjacent the pivot, are rounded to permit the transversely movement of the legs in opposite directions to form the opening designed for fitting over the head of the person carrying the umbrella and shown by the dot-dash lines in Figure 1.

At the bottom, the recesses in the lower legs are attached on opposite sides of a protrusion or tongue (not shown) in the free end of the following described bottom segment 14.

The bottom segment 14 is identical with the previously described top segment and is slidably inserted in a longitudinal bore formed through one end of a handle member 26 which may have a land at the opposite end as illustrated. A collar 27 is attached over the open end of the handle member in such a manner that the outer edge is beyond the pivot point 28 which construction limits the spread of the lower legs in the raised position of the umbrella while the slidable insertion of the segment permits locking the legs in the closed position. Any suitable means (not shown) may be used to retain the bottom segment 14 locked in any desired position of the bore of the handle member.

In operation:

By virtue of the construction of the stick, the collar 11 will slide over the entire length thereof when the leg members of the linkage system are collapsed. In the closed position of the umbrella, the collar may be fastened adjacent the handle member in the usual manner. In the raised position of the umbrella, after the collar 11 has been moved beyond the pivoted end of the tongue 15 and with the bottom segment adjacent the opening in the handle member, the upper and lower half-round legs can be pulled outwardly to the dot-dash positions shown in Figure 1. The legs are prevented from moving transversely in the opposite direction by rounding only the inner end extremities of the legs and plate, that is on the side opposite the direction of rotation at the pivotal connecting points of the upper and lower legs. By providing the shoulder on the inner end of the recess of each leg, each upper leg will receive a substantial amount of support from each lower leg in the opened position of the covering. Further maintaining the legs rigid in the opened position are the two notches 29 and 30 (Fig. 4) formed along the bottom of the outer edges of the rounded end extremities of the upper legs and coacting with the collar 11 which when free in the raised position of the umbrella will slide toward the legs and be held in the notches. The angle formed by the lower legs 20 and 21 with the handle member can be varied merely by varying the position of the pivot 28 in the handle member relative to the outer edge of the collar 27. If desired, the angle formed by the lower legs with the handle member, the limits of the transverse movement of the legs, and the locking position of the collar in the notches may all be correlated so that a substantial support for the umbrella in the open position is provided. A sudden gust of wind against the inner surface of the umbrella covering in the open position will move the collar 11 out of the notches 29

and 30 to permit the ready collapse of the legs of the linkage system and quick movement of the covering to the closed position.

It will be understood that the invention is not limited to the exact disclosure herein described but may lend itself to a variety of expressions within the scope of the appended claims.

What is claimed is:

1. A stick for the slidable collar of an umbrella, the stick comprising a top segment and a bottom segment, the top segment being of circular cross section with a diameter substantially equal to the inside diameter of the collar, a transversely expansible linkage system intermediate the top and bottom segments, the linkage system comprising two upper legs of equal length and two lower legs of equal length, each leg having a flat bottom surface subtending a surface of semi-circular cross section on a radius substantially equal to that of the top segment, means for pivotally securing one end of each lower leg to one end of each upper leg, means for pivotally securing the free end of each upper leg to one end of the top segment and the free end of each lower leg to one end of the bottom segment, the flat bottom surfaces of the legs being superposed in the closed position and the top segment and the superposed legs forming a continuous guideway for the collar, and means in the upper legs coacting with the collar for limiting the pivotal movement of the legs in the opened position thereof.

2. A stick for the slidable collar manipulating the covering of an umbrella to the opened and closed positions; the stick comprising a cylindrical top segment and a cylindrical bottom segment, said top segment being adapted for the slidable movement of the collar thereover, said top segment further having a longitudinal slot formed in one end, a tongue for the slot, means for securing one end of the tongue in the slot with the free end of the tongue protruding beyond the slotted end of the segment and with the sides of the tongue flush with the surface of the segment; the stick further comprising a transversely expansible linkage system of two members intermediate said tongue and bottom segment, each of said members comprising an upper leg and a lower leg, each leg having a flat base subtending a surface of semi-circular form on a radius substantially equal to that of said top segment, each upper leg further being of equal length and each lower leg being of equal length and of greater length than said upper legs, means for pivotally securing one end of each upper leg to one end of each lower leg, means for pivotally securing the free ends of said upper legs to opposite sides of said tongue, the end extremities of the upper legs adjacent said top segment being rounded and having on opposite sides thereof a notch coacting with the collar in the opened position of said legs, means for pivotally securing the free ends of the lower legs to opposite sides of said bottom segment, the flat base portions of said upper and lower legs being superposed in the closed position thereof means in the pivotally connected ends of said upper and lower legs for limiting the movement thereof to opposite directions and handle means for the bottom segment adapted to limit the transverse movement of said lower legs in the opened position.

3. A stick for the slidable collar manipulating the covering of an umbrella to the opened and closed positions according to claim 8 in which

the handle means comprises a substantially cylindrical body, said body having a land formed at one end and a central longitudinal bore formed in the opposite end, the length and diameter of the bore being greater than the corresponding dimensions of the bottom segment slidably inserted therein, and a collar for the cylindrical body removably disposed over the open end of the bore, with the lower legs passing therethrough.
